UNITED STATES PATENT OFFICE.

HARRY J. FRENZ, OF PHILADELPHIA, PENNSYLVANIA.

DESIGN FOR A RADIOCABINET.

Application filed September 27, 1928. Serial No. 28,292. Term of patent 7 years.

To all whom it may concern:

Be it known that I, HARRY J. FRENZ, a citizen of the United States, and a resident of Philadelphia, in the county of Philadelphia and State of Pennsylvania, have invented the new, original, and ornamental Design for Radiocabinet, of which the following is a specification.

Reference is had to the accompanying drawing forming part thereof, wherein—

The drawing is a perspective view of a radiocabinet showing my new design.

I claim:

An ornamental design for a radiocabinet as shown.

Signed at Philadelphia, in the county of Philadelphia and State of Pennsylvania, this 22nd day of September, A. D. 1928.

HARRY J. FRENZ.
